SKATE

William Blochinger, St. Paul, Minn., assignor to
 Olympiad Skate Co., St. Paul, Minn., a co-
 partnership composed of Almond L. Colbourn-
 sen and William Blochinger

Application January 13, 1936, Serial No. 58,847

10 Claims. (Cl. 280—11.18)

My invention relates to skates and particularly to the toe end of a skate, and has for an object to provide a skate having a toe end adapted to more effectively perform its intended function.

5 Another object of the invention resides in providing a toe end which will support the skater without unnecessarily digging into the ice.

An object of the invention resides in providing a toe end which will not readily injure the skater's 10 clothing.

A still further object of the invention resides in providing a toe end which is self cleaning.

Another object of the invention resides in providing a skate having a toe end which may be 15 used equally as well for braking as for jumping.

An object of the invention resides in providing a skate by means of which either abrupt or gradual braking may be procured.

Another object of the invention resides in providing a toe end having a zig zag ridge.

A feature of the invention resides in providing a toe end in which the ridge is confined solely to the face of the toe end.

An object of the invention resides in providing 25 a toe end in which irregularities in the face thereof are produced by cutting notches or grooves alternately in the opposite corners of the toe end, the notches extending through the face and the lateral surface of the toe end associated with the 30 particular corner in which the notch is cut and falling short of the opposite lateral surface.

Other objects of the invention reside in the novel combination and arrangement of parts and in the details of construction hereinafter illustrated and/or described.

In the drawing:

Fig. 1 is a perspective view of a figure skate illustrating an embodiment of my invention.

Fig. 2 is a side elevational view of a portion of 40 the structure shown in Fig. 1.

Fig. 3 is a front elevational view of the structure shown in Fig. 2.

Fig. 4 is a perspective view of the toe end of the 45 skate shown in Fig. 1 and drawn to an enlarged scale.

In the construction of skates and particularly figure skates, the practice has been to provide prongs at the toe end of the skate arranged alternately along the corners of the toe end. Such 50 construction is disadvantageous in that the spaces between prongs readily fill up with ice, thus lessening the usefulness of the structure for the desired purpose. Such prongs frequently catch in the skater's clothing, occasionally tripping the skater and frequently tearing his clothing. In

addition, the prongs readily bend or spread apart when the skater walks on the toe of the skate either on a wood floor or walk or on any other hard surface. When the toe end of the skate is used for braking, at times too much resistance is provided and the skate digs too deeply into the ice. The same frequently occurs when the skater uses the toe end in jumping. The present invention overcomes all of these disadvantages, as will become apparent from the following description. 10

For the purpose of illustrating the application of my invention, I have shown in the drawing a conventional type of figure skate which is indicated in its entirety by the reference character A. It will become readily apparent, however, that the 15 invention may be used with any type of skate.

The skate A comprises a runner 10 constructed of heavy sheet steel which is cut in the form shown in Fig. 1. This runner has a heel end 11, a toe end 12 and an intermediate portion 13, the toe end curving upwardly from the intermediate portion at the forward end of the skate. The face of the intermediate portion 13 of runner 10 is designated by the reference numeral 14 and constitutes the surface of the runner which slides 20 along the ice. This surface extends upwardly along the toe end 12 where said surface is designated by the reference numeral 15. Both the surfaces 14 and 15 may be transversely hollow ground or concave, or the same may be filed or 25 ground transversely straight. The lateral surfaces of the toe end 12 are indicated by the reference numerals 26 and 27 and the corners formed between these surfaces and the face 15 are designated by the reference numerals 28 and 29. 30

The skate A is attached to the shoe of the wearer by means of a heel plate 16 and a sole plate 17. Heel plate 16 is mounted on a stanchion 18 issuing upwardly from the heel end of runner 10 and may be welded or brazed thereto or secured to said stanchion in any other suitable manner. Sole plate 17 is similarly mounted on a stanchion 19 issuing upwardly from the intermediate portion 13 of runner 10 and on the uppermost part 21 of the toe end 12. This plate may also be welded or brazed to the stanchion 19 and toe end 12. The two plates 16 and 17 are provided with screw holes 22 through which suitable screws may be inserted for the purpose of attaching the skate to the shoe of the wearer. 35

The invention proper comprises irregularities in the face 15 of the toe end which are indicated generally by the reference numeral 23. These irregularities consist mainly of a zig zag ridge 24 which extends throughout the major portion of 40 45 50 55

the face 15 and is confined to the surface of the said face. The said irregularities also include one or more teeth or prongs 25 disposed at the lowermost end of the ridge 24. These parts of 5 the invention will now be described in detail.

The ridge 24 is formed by cutting two series of notches 31 and 32 in the toe end 12, the notches 31 being cut in the corner 28 and the notches 32 in the corner 29. All of these notches are 10 similar in construction, being V shaped grooves which extend diagonally through the corners 28 and 29. These notches have walls 35 and 36 and the reentrant angle included therebetween is designated by the reference numeral 37. The 15 line of intersection of the surfaces 35 and 36 is indicated at 38 and constitutes the vertex of the angle 37. The notches 31 extend through the surface 26 and also through the face 15 of the toe end 12 and fall short of the surface 27. These 20 notches are spaced from one another and are so formed that the lines of intersection 33 and 34 of said notches with the surface 26 approach each other toward the face 15, being spaced apart at such surface an amount equal to the width of the 25 ridge 24 at such locality. Where a sharp ridge is desired, the lines 33 and 34 may meet, depending upon the sharpness of the vertex 38 of the re-entrant angle 37 formed between the walls 35 and 36 of said notches. The notches 32 are constructed identically the same as the notches 31 and are staggered with respect thereto, being formed in the metal of the corner 29 between the notches 31. These latter notches extend through the surface 27 and face 15 and fall short of the 30 surface 26 in exactly the same manner as the notches 31. The ridge 24 is formed at the intersections of the surfaces 35 and 36 with the face 15 and hence lies wholly within said face. Due to the alternation of the notches 31 and 32, 35 said ridge becomes zig zag in shape extending alternately diagonally from one surface 26 of the toe end 12 to the other surface 27 thereof.

The tooth 25 is V shaped in cross section, being formed by means of a groove 39 also V shaped 40 which extends transversely across the toe end 12, being at right angles to the medial plane of the runner 10. One wall 42 of this tooth is formed by a surface of said groove. This tooth is further formed by another similar groove 41, one 45 surface of which forms the wall 43 of said tooth and the other surface of which merges into the face 14 of the intermediate portion 13 of the runner 10 of the skate. The tooth 25 is formed with a straight transverse ridge 44 which extends directly across the toe end 12 of the skate, and 50 which is free from the ridge 24.

The use of the skate is as follows: During normal travel over the ice the skate rests upon the face 14 which supports it for sliding movement, 55 either in a straight line or curved line. When abrupt braking is desired, the skate is turned so that the tooth 25 engages the ice, which digs into the ice and produces the desired result. When less effective braking is desired, the skate is turned 60 still further and the zig zag ridge 24 engages the ice. Due to the continuity of this ridge the irregularities formed thereby dig into the ice a lesser amount and less effective braking results. When the skater is jumping and desires to land 65 and remain stationary the toe end 12 is used. In such case the skate is turned so that the ridge 24 engages the surface of the ice when the skater lands. Said ridge in such position supports the skater and digs into the ice sufficiently to prevent slipping. 70

The advantages of my invention are manifest. By means of the formation and arrangement of grooves, the irregularities are self cleaning and the ice loosened is automatically forced out of the grooves as the use of the toe end is repeated. 5 The ridge of my invention being continuous is very strong and the bending and dulling of the prongs of the ordinary skate is eliminated. The irregularities of my invention will not readily catch on the skater's clothing. With my invention several degrees of braking can be procured. My invention operates better in soft ice than the ordinary skate and particularly where the weight of the skater is resting upon the toe end of the runner. The skater may walk along board walks 10 on the toe end of skates constructed with my invention without materially injuring the skates. 15

Changes in the specific form of my invention, as herein disclosed, may be made within the scope of what is claimed without departing from 20 the spirit of my invention.

Having described my invention, what I claim as new and desire to protect by Letters Patent is:

1. In a skate, a runner provided with a toe end, having a face, said face being constructed with 25 staggered depressions disposed on opposite sides thereof and forming a zig zag ridge extending along said face.

2. In a skate, a runner provided with a toe end having lateral surfaces and a face intersecting 30 said lateral surfaces, the corners between said lateral surfaces and face being formed with notches, the notches in one corner being disposed in staggered relation with respect to the notches in the other corner and forming in conjunction 35 with one another a zig zag ridge lying entirely in said face.

3. In a skate, a runner provided with a toe end having lateral surfaces and a face intersecting 40 said lateral surfaces and forming two corners therebetween, one of said corners being formed with spaced notches extending through said face and the lateral surface associated with said corner and falling short of the opposite lateral surface and the other corner being formed with 45 similar notches staggered with respect to the first named notches.

4. In a skate, a runner provided with a toe end, having a face and a ridge confined entirely to said 50 face and extending along a continuous irregular line in said face.

5. In a skate, a runner provided with a toe end having lateral surfaces and a face intersecting 55 said lateral surfaces and forming two corners therebetween, one of said corners being formed with spaced V shaped grooves extending through said face and the lateral surface associated with said corner and falling short of the opposite lateral surface, the other corner being formed 60 with similar grooves staggered with relation to said first named grooves and forming in conjunction therewith a zig zag ridge extending in a continuous line and being confined entirely to said face.

6. In a skate, a runner provided with a toe end, having a face, said face being constructed with 65 staggered depressions disposed on opposite sides thereof and forming a zig zag ridge extending along said face, and a tooth formed in the toe 70 end at one end of said ridge.

7. In a skate, a runner provided with a toe end, having a face, said face being constructed with 75 staggered depressions disposed on opposite sides thereof and forming a zig zag ridge extending

- along said face, and a tooth formed in the toe end at the lowermost end of said ridge.
8. In a skate, a runner provided with a toe end, having a face, said face being constructed with 5 staggered depressions disposed on opposite sides thereof and forming a zig zag ridge extending along said face, and a tooth formed in the toe end at one end of said ridge, said tooth being spaced from the end of said ridge.
- 10 9. In a skate, a runner provided with a toe end, having a face, said face being constructed with staggered depressions disposed on opposite sides thereof and forming a zig zag ridge extending along said face, and a tooth formed in the toe end at one end of said ridge, the point of said tooth 15 lying in said face.

10. In a skate, a runner provided with a toe end having lateral surfaces and a face intersecting said lateral surfaces and forming two corners therebetween, one of said corners being formed with spaced V shaped grooves extending through 5 said face and the lateral surface associated with said corner and falling short of the opposite lateral surface, the other corner being formed with similar grooves staggered with relation to said first named grooves and forming in conjunction therewith chisel edges confined entirely to said face and extending along the same in zig 10 zag formation, said chisel edges when in contact with the ice being substantially parallel therewith.

WILLIAM BLOCHINGER.
